MEANS FOR SEGREGATING CURRENTS OF DIFFERENT FREQUENCIES IN ELECTRICITY-CONDUCTING SYSTEMS.

1,284,743.

Specification of Letters Patent. Patented Nov. 12, 1918.

Application filed August 31, 1915. Serial No. 48,357.

To all whom it may concern:

Be it known that we, LOUIS T. MERWIN and ROY K. FREEMAN, citizens of the United States, and residents of Portland, county of Multnomah, State of Oregon, have invented a new and useful Improvement in Means for Segregating Currents of Different Frequencies in Electricity-Conducting Systems, of which the following is a specification.

10 This invention relates to means for segregating and conducting along individual paths certain selected frequencies present in the circuit of an alternating or pulsating 15 electrical current.

In electricity conducting systems which carry alternating or pulsating currents, a plurality of frequencies varying in phase and magnitude are carried by the conductors, some of these frequencies being primarily developed in the system and others being induced into the system.

20 Detecting instruments located in the circuit are adapted to respond to certain frequencies and the presence of other interfering frequencies in the circuit of the instrument tends to reduce the efficiency of the latter.

25 In a prior patent application filed by us on Feb. 5th, 1915, Ser. No. 6,383, under title "Method and means for eliminating disturbing frequencies in electricity conducting systems", we illustrated a type of selective transformer, by the action of which, certain selected frequencies were eliminated 30 from the system.

In the present application, the main object 35 of the invention is not to eliminate these selected frequencies from the circuit but to short-circuit them about the detecting instrument and allow only the frequencies to be used to pass through the instrument.

40 We attain this object of our invention by making use of the properties of the impedances which exist in circuits of the character described. The impedance in an alternat-

ing or pulsating current is expressed by the following formula, assuming sine waves:

$$Z = \sqrt{R^2 + \left(2\pi fL - \frac{1}{2\pi fC}\right)^2} \quad 50$$

in which

Z equals impedance
R " ohmic resistance
f " frequency
L " inductive reactance
C " condensive reactance. 55

It will be observed by an inspection of this formula that the impedance is a function of the frequency, *i. e.* with a given inductance and capacity, the impedance will vary with the frequency. Furthermore, it will be also observed that the impedance does not vary directly as the frequency. 60

65 Therefore, assuming that we introduce into a circuit a shunt which contains impedance having a low value for one frequency and having a higher value for all other frequencies, and assuming further the continuation of the main circuit with impedance having a high value for the first mentioned frequency and a lower value for some other frequency, it will be obvious that the circuit will be divided so that the first 70 mentioned frequency will flow through the shunt circuit, and all other frequencies will flow through the continuation of the main circuit. Detecting instruments may be placed in either path and will respond to 75 the frequencies flowing through that path.

The use of this principle has many useful adaptations, of which the following examples are typical: In a telephone line, paralleling a power line, induced frequencies of 80 low value pass through the receiver and interfere with the high talking frequencies. In multiplex telegraphy, a plurality of different frequencies may be segregated and conducted along individual paths through 85 detecting instruments adapted to respond to the particular frequencies. In wireless tele-

graphy, selective signal work, and many other forms of electrical endeavor, this principle may also be used to great advantage.

In the accompanying illustrations, are 5 shown three adaptations of our device, and in these illustrations,

Figure 1 is a diagrammatic view showing the multiple arrangement of the device for short-circuiting a low frequency or group 10 of low frequencies across the line.

Fig. 2 is a similar view showing the multiple arrangement of the device for short-circuiting a plurality of selected frequencies across the line, and

15 Fig. 3 is a view showing a series arrangement of the device for short-circuiting a particular frequency around the detecting instrument.

20 a and b represent the conductors of an alternating or pulsating electricity circuit, and D is a detecting instrument located in the line.

In Fig. 1, it is assumed that an induced 25 low frequency in the line interferes with the high frequency to be used in the operation of the detecting instrument. Therefore, a short-circuit conductor e is connected 30 to the conductor a at the point A and this conductor is divided into the two branches f and g . Adjustable condensers C' and C^2 are placed in the branches f and g , respectively, and an adjustable inductance L^2 is also placed in the branch g . The branch conductors f and g are then mutually re- 35 lated by being differentially wound as indicated by f' and g' around a core of high magnetic permeability preferably closed iron core M, and connected to the conductor b , at the point B by a conductor h . An ad- 40 justable condenser element C is placed in the conductor a , between the detector D and the short-circuit conductor e .

The action of this net-work in short-circuiting the selected low frequency is as fol- 45 lows:

Assuming a plurality of various frequencies to be present in the conductor a , one of which frequencies we will call F, a portion 50 of the current in a , flows through e and divides into the branch conductors f and g .

Assuming the ohmic resistance to be negligibly small, any arbitrary choice of value for C' will give a certain potential drop in the branch f for the frequency F.

55 The reactance members C^2 and L^2 are next adjusted so that the drop in potential in the branch g will be equal to that in the branch f , for said frequency F. If, now, the branches f and g are connected to the 60 conductor b , equal currents of the frequency F will flow through said branches. For all the other frequencies, however, the imped- 65 ances will have different values, and conse- quently the potential drop in the branch f

will not equal the potential drop in the 65 branch g . Unequal currents of other fre- quencies will then flow in these branches. In speaking of potential difference between two points, currents or magnetic fluxes, we consider them as vector quantities, and here- 70 after when they are spoken of as being equal, we mean that they are equal as vector quantities.

If now, the branches f and g are in- 75 ductively related so that further impedances are introduced which will have a low value for equal currents and a high value for unequal currents, the branches f and g become true short-circuit paths for the frequency F, only, and paths of high impedance for all 80 other frequencies.

So it may be said that the function of the 85 differential winding is to offer a path of low impedance for the currents of a certain frequency in the two branches that have 90 been made equal in phase and magnitude by adjustment of the impedances in those branches, but which offers at the same time a path of higher impedance for currents of all other frequencies.

This inductive relationship between the 95 two branches may be brought about by pro- 100 viding the differential windings f' and g' on a closed iron core M so as to assure the least possible magnetic leakage. This means 105 a closed magnetic circuit with a closely over- lapped and intermingled pair of windings, and the point H at which the conductor h is connected to the windings is of course to be so chosen that the magnetizing forces impressed on these mutual inductance coils 110 are equal in phase and magnitude for cur- rents of the same phase and frequency, but unequal in phase and magnitude for unequal 115 currents.

With said mutual inductance introduced 120 into the branches f and g , these branches be- 125 come true short-circuit paths of low im- pedance for frequency F, but paths of high impedance for all other frequencies. Hence, 130 currents of other frequencies will be choked back out of the short-circuit path, and con- ducted on through the detecting instrument D with very slight leakage, while the fre- 135 quency F will be short-circuited past the 140 instrument.

In Fig. 2, the arrangement of the short- 145 circuited net-work is substantially equiva- 150 lent to that shown in Fig. 1, the difference 155 being that the latter is arranged to select and short-circuit a plurality of frequencies. For this purpose there are connected in mul- 160 tiple with the conductor g the additional 165 paths m and n , in which are contained the condenser and inductance elements C^3 , C^4 , L^3 , and L^4 , located respectively as shown in 170 this figure.

It has been seen by the description relat-

ing to Fig. 1, that the frequency F was short-circuited across the line from A to B while the other frequencies were conducted past the point A through the detector D . In 5 this case, let us assume that two other frequencies F_1 and F_2 are also to be short-circuited across the line. Leaving the setting for C , as originally made the condenser C^s and inductance L^s are so adjusted that the 10 impedance in the branch m for the frequency F , will be equal to the impedance in the branch f for the same frequency F . In this connection, there is to be remembered, the statement, *supra*, that the impedance C' may 15 be of any value, and the impedance C^2 in the branch g is adjusted to form a path of lower impedance for branch f . And there are similar adjustments of the values of the impedance in the branches m , n . The imped- 20 ances in the branches g , m , n , are independ- ent of each other, or, in other words, the re- lation of the branch f to branch g does in no 25 wise impair the relation of branch f to branch m , or to branch n .

25 The frequency F , will then be short-circuited in a manner similar to frequency F . Similarly a frequency F_2 may be short-circuited through the reactance branch n , when the latter is used in combination with the 30 branch f .

And it is now evident that for any setting of C' , and using any number of branches such as g , m , n , the impedances in these lat- 35 ter branches may be so adjusted as to form short-circuit paths for various frequencies; that is to say, each branch through its mu- tual relation to C' being adapted to short- circuit one particular frequency.

It is also apparent that the short-circuit 40 branch may be treated as an original cir- cuit, and sub-short-circuits provided as de- sired with detecting instruments placed in such circuits.

By continuing the arrangement shown in 45 Fig. 2, it is evident that under ideal con- ditions, any number of frequencies may be short-circuited.

In Fig. 3, the arrangement shows the same 50 short-circuit net-work detailed in Fig. 1. In this net-work however, the conductor h is connected to the conductor a , and the short-circuited frequencies are merely car- ried around the detecting instrument D in- stead of across the line.

In this case, the inductance L is substi- 55 tuted for the condenser C in Fig. 1 for the purpose of permitting high frequencies to be short-circuited around the detector D , and low frequencies allowed to pass through the latter. 60

We claim:

1. In an electricity conducting system of the character described, means for segregat- 65 ing a certain frequency comprising a main circuit provided with a shunt, the latter be- ing divided into branches, impedances in such branches, and differential windings connected with said branches, through which said branches are mutually related.

2. In an electricity conducting system of 70 the character described, means for segregat- ing a certain frequency comprising a main circuit provided with a shunt, the latter be- ing divided into branches, impedances in such branches, the impedance of one branch 75 being adjustable, and differential windings connected with said branches, through which said branches are mutually related.

3. In an electricity conducting system of 80 the character described, means for segregat- ing a certain frequency comprising a main circuit provided with a shunt, the latter be- ing divided into branches, impedances in such branches, and a core having differ- ential windings, connected with said branches, 85 through which said branches are mutually related.

4. In an electricity conducting system of 90 the character described, means for segregat- ing a certain frequency comprising a main circuit provided with a shunt, the latter be- ing divided into branches, impedances in such branches, and a core of high perme- ability having differential windings, con- 95 nected with said branches, through which said branches are mutually related.

5. In an electricity conducting system of 100 the character described, means for segregat- ing a certain frequency comprising a main circuit provided with a shunt, the latter be- ing divided into branches, impedances in such branches, the impedance of one branch being adjustable, and a core having differ- ential windings, connected with said 105 branches, through which said branches are mutually related.
